UNITED STATES PATENT OFFICE.

JOHN COLLINS CLANCY, OF ASBURY PARK, NEW JERSEY.

PROCESS OF MANUFACTURING HYDROCARBONS AND CYANIDES.

No Drawing.

Application filed April 18, 1925. Serial No. 24,270.

To all whom it may concern:

Be it known that I, JOHN COLLINS CLANCY, citizen of the United States, and resident of Asbury Park, in the county of Monmouth and State of New Jersey, have invented certain new and useful Improvements in the Processes of Manufacturing Hydrocarbons and Cyanides, of which the following is a specification.

10 This invention relates to the manufacture of hydrocarbons and cyanide; and it comprises a method of destructively distilling solid carbonaceous material while the latter is immersed in a fused cyanide reagent, and

15 in this connection involves the employment or combination therewith of a cyanide making process, through the intermediacy of which, the cyanide decomposed in the distilling step is reconstituted from the distillation residues, and the recovery of the cyanide content from the latter automatically effected by utilizing said residues in the manufacture of additional cyanide. The

20 carbonaceous material may be in the nature of carbohydrates, sawdust, bitumen, peat, lignite, and in particular,—coal.

The object of this invention is to recover from the aforesaid material, particularly coal, higher percentages of liquid hydrocarbons than are obtained by any of the hitherto practised processes of destructive distillation, and to reclaim the cyanide reagent from the distillation residues while utilizing the latter to manufacture additional cyanide that the cost, not only of the cyanide recovery step, but also that of the distilling operation is thereby very much reduced in that it enables the profitable utilization of non-coking or poorly coking coals or other solid fuels heretofore not successfully treated by destructive distillation processes.

In my pending application entitled: Process of cracking oils Serial No. 586,029; filed September 2, 1922 I have disclosed the use of molten cyanide in the treatment of carbonaceous material, such as shale and coal for the production of hydrocarbons therefrom. In operating the process as described in said application, I separated the coky residuum or finely divided carbon from the molten cyanide contained in the fusion reaction products by filtration of the latter

through iron turnings; this method affording sufficient separation of the finely divided carbon resulting from the cracking of oil with molten cyanide. Using this method on the fusion residues resulting from the treatment of coal with molten cyanide, however, a difficulty became apparent, unforeseen when operating on a small scale; namely that the increasing coky residuum absorbs large quantities of the sodium cyanide reagent, and even after filtering or liquating out the surplus cyanide from the carbonaceous residuum at a red heat, as much as 20 to 25% of the cyanide is still trapped in the coky residuum. Obviously of course this may be recovered from the coky mass by suitable leaching, but any such procedure obviously involves considerable expense, imposed upon a process already burdened by the low market value of some or all of its reaction products.

I have therefore sought and have found such a combination of steps as will not only permit of the economic utilization of cyanide for the formation of hydrocarbons from coal as disclosed in my said co-pending case; but which will further afford an efficient recovery of said cyanide, moreover, while satisfactorily accomplishing these results, I have succeeded in going still further, in that my present process not alone affords liberation of the cyanide trapped in the coky mass, but actually gives more than one hundred percent of cyanide yield therefrom.

In brief, I do not remove the cyanide from the coky mass but rather I remove the coky mass from the cyanide by fixing the carbon thereof in the form of additional cyanide.

According to my invention, carbonaceous material either in the form of sawdust, carbohydrates, bitumen, peat, lignite, or coal, and particularly the latter, is reduced to a finely divided state and admixed with a suitable hydrocarbon oil, such as petroleum, shale oil, heavy tar oil, or the like, to form an emulsion or suitable mixture. This mixture, advantageously in a preheated condition, is then commingled with molten cyanide reagent and distilled under carbonizing temperatures and under pressure which can be regulated so as to produce from the

coal, a large proportion of hydrocarbon oils. The moisture content of the coal reacts with the molten cyanide to produce ammonia which in part decomposes and tends to hydrogenate the coal to produce larger yields of saturated hydrocarbons.

Other side reactions take place between the decomposition products of the cyanide and the coal, to form free hydrogen and carbon monoxide, the latter reaction tending to further hydrogenate the coal. Dry ammonia gas, may be advantageously bubbled through the molten mixture during the latter part of the distilling operation, to assist in the agitation of the fusion products; and which gas, towards the end of the distilling operation, reacts with the cyanide decomposition products in the presence of carbon to promote a cyanide forming reaction. Permanent hydrocarbon gases, such as "still" gases, may be advantageously used in conjunction with the ammonia gas to further assist in said agitation. The evolved hydrocarbon vapors and gases are suitably collected.

The fusion residues left in the still, comprising carbonaceous residuum, alkali metal cyanide and its decomposition products,—are discharged from the still preferably as a free flowing molten magma which is thereafter treated to reconstitute the cyanide decomposed by the moisture content of the coal, and to recover the cyanide from said magma and also to utilize the latter in the manufacture of additional cyanide in the manner hereinafter described.

In carrying my process into practice, I first charge molten cyanide reagent into a closed vessel or still made of any suitable material, such as iron. The charging is continued until the still is about half filled with said cyanide. The cyanide used may be sodium cyanide of commercial purity, with a melting point around 500° C.; the low melting point of the latter compound being due to impurities such as sodium sulpho-cyanide, and other alkalinous metal compounds. The cyanide is maintained in the molten condition within the still by the application of heat thereto. The mixture of coal and oil, prepared as described in the foregoing paragraph, is slowly introduced at a low point in the still so that it enters well below the surface of the bath of molten cyanide. As the oil-coal mixture is fed in, the pressure inside the still rises while the coal is commingled by the agitation of bubbling of the oil vapors through the depth or bath of the molten cyanide. The pressure is regulated according to the temperature desired in the still. A convenient pressure is about sixty pounds per square inch, but this pressure may be varied up or down during the introduction of the coal. As vapors from the oil first pass off into the vapor

space of the still during the charging of the coal-oil mixture, the pressure thereby imposed upon the coal (especially if the coal is of the bituminous variety) causes the latter to first melt and become more or less miscible with the molten cyanide thereby presenting an extensive surface to the cyanide for reaction therewith. After the still has received its quota of coal and oil mixture; namely, a proportion of coal approximately equal to about half the weight of the volume of the molten cyanide used, I gradually release the pressure and carry on the distillation of the volatile matter either under atmospheric pressure or in a vacuum, but preferably around atmospheric pressure. During the latter operation I prefer to gradually increase the temperature of the molten body in the still up to say around 700° C.; the vapors evolved during the distilling operation being suitably collected and condensed.

A convenient form of still is a cylinder or a tube with an agitator or with a worm or spiral agitator moving the mixture forward to the discharge end but any ordinary still of suitable material such as iron may also be used with or without an agitator.

After the completion of distillation, the carbonaceous residuum or finely divided coke left in the still, remains largely in suspension in the molten cyanide mixed with its decomposition products. To insure suspension of the coky residuum in the molten bath I continue the bubbling of "still" gases therethrough until the molten magma is ready for discharging. If insufficient cyanide has been used, the residual products give rise to a sticky molten magma which is difficult to discharge from the still and requires the addition of a further quantity of molten cyanide to facilitate its discharge therefrom. It is advisable to add at the start, sufficient cyanide to prevent the formation of such sticky fusion residues.

We are now confronted with the problem of the recovery of the cyanide. Filtration or liquation of a portion of the cyanide from the fusion residues might be resorted to; provided that such fusion residues had not been allowed to become too concentrated in coky residuum. However, as such an operation does not reconstitute the cyanide decomposed by the moisture content of the coal, nor, does it recover the cyanide absorbed or trapped in the coky mass—it is preferable not to undertake such filtration or liquation, in view of my discovery of the feasibility of so treating these coky residues as to, in effect separate these coky residues themselves from the cyanide entrapped therein, rather than to remove the said cyanide from the said residues. In other words, I have found it to be the much more economical course, to remove the trap-con-

stituting residuum bodily, so to speak, from the entrapped substance, in contradistinction to any attempt to remove the latter from the former.

5 I have made the discovery that the coky residuum in question admixed as it is, with cyanide and with the decomposition products of cyanide,—is peculiarly well adapted to participate in a reaction with alkalinous metal carbonate, such as sodium carbonate, and nitrogen or a nitrogenous gas to not alone reconstitute the decomposed cyanide, but to further form additional cyanide, the carbon of the residues being the source of 15 the carbon content of such additional cyanide.

This reaction is effected at a cyanide forming temperature, the carbonate being admixed with the still molten and hence highly 20 heated residues aforesaid, and the nitrogen or its equivalent, being bubbled up through the molten mass, in a suitable furnace, such as is ordinarily used for making cyanide by the Bielby or Castner processes.

25 Thus, the very substance which would ordinarily be regarded as a source of trouble and expense, and from which the trapped cyanide could normally be separated only at considerable expense,—is caused to free 30 this trapped cyanide by being itself combined with other substances to form an additional and auxiliary quantity of the substance being freed,—to wit,—cyanide.

The molten cyanide produced in the foregoing manner is usually contaminated with more or less finely divided carbon, this carbon, however, is readily separated by simple filtration from the cyanide while the latter is in the molten state. The residue of carbon 40 after filtration still contains more or less absorbed cyanide. This residue may be treated with steam to produce ammonia from its cyanide content, by this well known method of cyanide hydrolysis. I have discovered that the ammonia so produced, after 45 being dried, may be used, advantageously, in admixture with nitrogen in the cyanide forming step. I have found that even as small an addition as 2% by volume of ammonia in admixture with nitrogen or in admixture with a carbonaceous gas containing nitrogen, greatly facilitates the fixation of nitrogen in the said cyanide forming step and that the temperature and time of such 50 reaction can be materially reduced by its use. The carbon residue from the aforesaid steaming operation may be leached with water to remove soluble salts and yield sulphur and ash free carbon, in other words, substantially pure carbon, the latter having a relatively high market value.

55 It is obvious that the cyanide reclaimed and manufactured in the cyanide forming step of the described process may contain as impurities, small quantities of other alka-

linous metal cyanides besides sodium cyanide, such cyanides, the base of which correspond to some of the alkalinous ash constituents of the carbonaceous material. For example, if sawdust be the carbonaceous material treated, some potassium cyanide will be formed in proportion to the potash content of this material. On the other hand, when treating coal, alkalinous cyanides and sulpho-cyanides of the alkali ash and sulphur content thereof will be formed. The aforesaid impurities however, do not accumulate, for the reason that, any portion of the cyanide reused in the process for treating additional quantities of carbonaceous material, is thereafter admixed with the fresh sodium cyanide produced through the intermediacy of the aforesaid cyanide forming step. By this means the percentage of impurities are kept more or less constant.

Owing to the presence of sodium sulpho-cyanide and other impurities referred to; any portion of the cyanide reagent used for treating additional quantities of coal will have a lower melting point than if pure sodium cyanide were used as a cyanide reagent or starting material. The low melting point of the cyanide reagent is especially advantageous in the treatment of bituminous coal, in that, when the latter is brought into contact with a cyanide reagent of low melting point, it commingles therewith without perceptible intumescence; this together with the property possessed by molten sodium cyanide of holding considerable quantities of finely divided coal or other carbonaceous material in suspension allows of its use in the treatment of a very large variety of solid fuels.

55 While I have described the method of destructively distilling comminuted carbonaceous material by admixing the latter with a suitable liquid hydrocarbon and then bringing this mixture into contact with molten cyanide, it must be understood, however, that the finely divided carbonaceous material, such for example as coal, may be introduced into the still without such admixture with liquid hydrocarbon. For example, finely divided coal may be delivered into contact with the molten cyanide by means of a suitable screw conveyer or other mechanical means. The preferred method, however, is to form a mixture of the finely divided coal with a suitable hydrocarbon liquid as described. The presence of the liquid hydrocarbon, such for example as a heavy oil acts to more or less soften the coal and functions as a kind of regulator of the destructive distillation of the coal while at the same time acts as a carrier for introducing the coal into contact with the molten cyanide.

130 The hydrocarbon oil so added or mixed with the coal will also distill over to a large

extent and be recovered with the hydrocarbon oils from the coal, but the principal function of the hydrocarbon oil is to facilitate as aforesaid the delivery of the coal to the molten cyanide in the still.

It is obvious that, instead of bringing the carbonaceous material into contact with the molten cyanide by the methods described; the carbonaceous material, for example, finely divided coal may be mixed with solid cyanide in the subdivided form and this mixture charged into the still and brought up to a destructive distillation temperature whereby the cyanide melts and reacts with the coal to produce hydrocarbons and other volatile reaction products, while at the same time supplying the fusion coky residuum for the cyanide forming step. Using this method, however, much of the moisture is driven off from the coal before it has the opportunity of reacting with the cyanide in the molten state to establish hydrogenating reactions as hereinbefore referred to. The preferred method is to use the cyanide in the molten state as described. The molten cyanide reagent used in the process may be obtained, after the process has been in operation, from any portion of the molten cyanide produced in the cyanide forming step of the process, thereby saving the expense and time required in heating solid cyanide to the melting point or to a molten state.

As indicated, sodium carbonate is the preferred alkali-base-supplying agent employed in the cyanide forming step of the process principally because it gives satisfactory results and is inexpensive. Instead of sodium carbonate I may employ other sodium salts, such as sodium hydroxide, sodium bi-carbonate or sodium salts of similar organic acids. Sodium carbonate, however is the logical alkali metal compound for use in the cyanide forming step of my process, and the distillation fusion residues are preferably admixed with the said carbonate while the latter is in the molten state to facilitate uniform mixture of the reactants.

What I claim is:

1. The method of manufacturing hydrocarbons and cyanides which comprises, destructively distilling solid carbonaceous material while the latter is immersed in a molten alkali metal cyanide reagent, collecting the volatile reaction products, reconstituting the cyanide decomposed in the distilling step and liberating cyanide trapped in the distillation residues, by subjecting the latter to a cyanide forming reaction in which participate sufficient alkali and nitrogen to combine with part at least of the carbon content of said residues to form additional alkali metal cyanide, thereby reclaiming cyanide reagent in admixture with the additional cyanide produced through the inter-

mediacy of the said cyanide forming reaction.

2. The process of manufacturing hydrocarbons and cyanides which comprises, subjecting to distillation a mixture of comminuted carbonaceous material, a heavy hydrocarbon oil and molten sodium cyanide, under suitable pressure and temperature, to produce hydrocarbons which are liquid at normal temperature and pressure, and a fusion residue containing coky residuum, mixing the said fusion residue with sodium carbonate, subjecting the so formed mixture to the action of a nitrogenous gas under alkali metal cyanide forming conditions to fix part at least of the carbon content of the said fusion residue in the form of additional sodium cyanide and to reconstitute the cyanide decomposed in the distilling step, thereby reclaiming the originally used quantity of sodium cyanide in admixture with the additional cyanide produced under said cyanide forming conditions.

3. The process of manufacturing hydrocarbons and cyanides which comprises, distilling a mixture of finely divided coal and a hydrocarbon oil in admixture with molten sodium cyanide reagent under suitable pressure and temperature, to produce hydrocarbons which are liquid at normal pressure and temperature, releasing the pressure and increasing the temperature towards the end of the distilling operation to drive off heavier volatile and liquefiable hydrocarbons and to obtain a fusion residue containing coky residuum, mixing the said fusion residue with sodium carbonate, subjecting the so formed mixture to the action of a nitrogenous gas under alkali metal cyanide forming conditions to fix part at least of the carbon content of said fusion residue in the form of additional sodium cyanide and to reconstitute the cyanide decomposed in the distilling step, thereby reclaiming sodium cyanide reagent in admixture with the additional sodium cyanide produced under said cyanide forming conditions.

4. The process of manufacturing hydrocarbons and alkali metal cyanides which comprises, destructively distilling finely divided coal while the latter is immersed in a molten sodium cyanide reagent under suitable pressure and temperature to produce liquid hydrocarbons and fusion residue containing coky residuum, reconstituting the cyanide decomposed by the moisture content of the coal and simultaneously liberating part at least of the cyanide trapped in the distillation residues, by subjecting the latter to a cyanide forming reaction in which participate sufficient sodium carbonate and nitrogen to combine with a portion of the carbon content thereof, and reusing, in part at least, the so liberated cyanide for treating additional quantities of coal.

5. The process of manufacturing hydrocarbons and cyanides which comprises, destructively distilling a mixture of finely divided coal and a hydrocarbon oil in admixture with molten sodium cyanide reagent under suitable pressure and temperature to produce liquid hydrocarbons and other volatile reaction products, releasing the pressure and increasing the temperature towards the end of the distilling operation to drive off heavier volatile hydrocarbons and to obtain a molten fusion residue containing coky residuum, collecting such hydrocarbons and volatile reaction products, mixing the aforesaid molten fusion residue with molten sodium carbonate, subjecting the so formed molten mixture to the action of nitrogen under alkali metal cyanide forming conditions to fix part at least of the carbon content of the said fusion residue in the form of additional sodium cyanide and to reconstitute the cyanide decomposed in the distilling step, thereby reclaiming the cyanide reagent in admixture with the additional cyanide produced under said cyanide forming conditions.
6. The process of manufacturing hydrocarbons and cyanides which comprises, destructively distilling comminuted coal while the latter is immersed in molten alkali metal cyanide, collecting the volatile reaction products, subjecting the distillation residues to a cyanide forming reaction in which participate sufficient alkali and nitrogen to reconstitute the cyanide decomposed in the distilling step and to form additional cyanide through chemical combination with a portion at least of the carbon content of said residues.
7. The process of manufacturing hydrocarbons and cyanides which comprises, destructively distilling comminuted carbonaceous material in contact with molten alkali metal cyanide, collecting the volatile reaction products, and subjecting the distillation residues to a cyanide forming reaction to reconstitute the cyanide decomposed in the distilling step and to form additional cyanide.
8. The process of manufacturing hydrocarbons and cyanides which comprises, destructively distilling a mixture of finely divided carbonaceous material and a hydrocarbon oil in contact with molten alkali metal cyanide, collecting the volatile reaction products, and subjecting the distillation residues to a cyanide forming reaction to reconstitute the cyanide decomposed in the distilling step and to form additional cyanide.

In testimony whereof, I affix my signature hereto.

JOHN COLLINS CLANCY.
